MACHINE FOR THE INTRODUCTION OF
INSERTIONS INTO BOTTLE CAPS

Anders Josef Jonsson, Linkoping, Sweden

Application August 18, 1931, Serial No. 557,872
In Sweden April 10, 1930

6 Claims. (Cl. 113—80)

The present invention relates to automatic means for the manufacture of caps, said machines being of the type provided with a tool for inserting a packing disk of cork or other material 5 into the cap which tool consists of two parts respectively movable towards and away from one another, one of which holds the cap inserted between said parts, whilst the other inserts the cork disk. These machines have in recent years 10 been improved in many respects so that their production capacity has been considerably increased. The object of this invention is to improve them still more by removing certain risks in connection with the cork inlaying. On perturbations in 15 the cork inlaying arising, for example, when a cap on account of some reason or other, does not arrive at the correct position in the cork inlaying stamp, but the cap and the cork disk become jammed together on the edge of the tools 20 and stick in the upper part of the tools, the cap may be ruined and part of the bottles be non-capped before the defect is discovered and it is possible to stop the machine. Further it may happen that a cork disk (fed automatically to the 25 cork inlaying tool) fails to arrive, or is broken resulting in that a bottle obtains a cap without a cork disk or a broken cap.

By the device according to this invention the machine is automatically and immediately 30 brought to stop if any of the above-mentioned perturbations should arise.

An embodiment of the invention used in a machine for capping bottles is shown as an example in the accompanying drawings wherein 35 Figure 1 shows in front elevation the upper part of a machine of approved construction, the right hand portion of the figure being shown in section, the plane of which is indicated on the line 1—1 of Figure 6.

Fig. 1^a is a horizontal section on the line 1^a—1^a of Fig. 1.

Figures 2 and 3 show details on a larger scale, viewed from the side, and having the parts in other positions than those in Figure 1. Figure 4 shows a modified detail, viewed from the side, and Figure 5 another detail, viewed from above. Figure 6 is a vertical section on the line 6—6 of Fig. 1.

Fig. 7 is a front elevation partly in section of 50 the lower part of the machine.

Fig. 8 is a fragmentary side elevation of the lower part also shown partly in section.

Referring now to the drawings, among the known parts of the machine 1 indicates the frame of the machine, 2 the crank and eccentric

shaft which drives inter alia the capping stamp 3 and the upper part 4 of the cork laying tool. 5 and 6 indicate the slide and connecting rod respectively of the capping stamp which receives its reciprocating motion from the crank 2^a. 7 and 8 indicate the slide and eccentric drive respectively of the part 4. The two slides 5 and 7 are movable in common guides in the frame 1. 9 indicates an arm extending from the slide 7, said arm serving as a support for the part 4. The reciprocating movement of the slide 7 is obtained by means of the eccentric drive 8 and a spring 8^a resting on the machine table and pressing against the arm 9. The spring is held in operative position by means of a bolt 8^b fixed in 15 the arm.

Among other parts already known there is the conveyor 12 which feeds cork disks, one at a time, from a supply pipe 13 to and below the part 4. This conveyor consists of a slide which obtains 20 a to and fro motion by means of a gear device 10, 14, 15, 16, the rack 16 of which obtains its motion from the drive shaft 2 by means of a crank 17 and a connecting rod 18. In Fig. 1 part of the pinion 14 is cut away in order to show 25 the pinion 15 sitting behind into which the rack 16 engages. In Figure 5 the conveyor is shown from above. The semi-circular recess 20 is suited to the cork disk. The conveyor works, as is known, in the way that, subsequent to each push 30 towards the part 4, it is drawn back such a distance that a cork disk in the tube 13 just above the conveyor falls into the recess 20 whereafter the conveyor pushes said cork disk below the part 4 and just over the insertion member 21 35 which operates from below.

The last-mentioned member is disposed in a bore of the machine table 22, and has imparted thereto by means of mechanism described below, an up and down motion such that it moves 40 upward, when a cork disk has been supplied by the conveyor and pushes said disk into the cap. A cap 23, is indicated in the drawings in a position ready to receive a cork disk 24. The part 4 which at its lower end is provided with a recess 45 formed in conformity with the cap has just engaged the cap. The part 21 is just moving upward in order to insert a cork disk 24 into the cap under which the part 4 holds it in position. During the first stage of its motion the part 4 50 centres the cap relative to the part 21. Then the part 4 moves upward and the part 21 moves downward again so far that the cap becomes free and may be conveyed further to the capping tool (not shown). There is no device shown for con- 55

veying the cap from the stamp 3 to the tool 4, thereof, if the rod 53 is disposed in the path of the shoulder 54, said rod 53 is moved downwardly. 5

5 The most simple and suitable one is a pneumatic device employed in this kind of capping machines in recent years.

10 The invention relates more particularly to the mechanism by which the insertion member obtains its motion. The purpose of the invention is to arrange in this mechanism or motion device a resilient connection of such nature that it gives to the insertion member a certain spring in its direction of motion so that, independent of the 15 rest of the motion device, it may stop if it meets an abnormal resistance during the insertion motion.

20 Below the table 22 is a two-armed lever or balance 26 mounted in a fork 27. One end of the balance is by means of a pivot 28 connected to the insertion member and by means of another pivot 29 connected to a vertical push rod 30. Above said rod there is another push rod 31 in alignment with the former. This rod 31 lies in 25 a bore 32^a in the member 32 fixed on the slide 7 and has its upper end forked to receive a roller 34 which, by a spring 36, acting on the forked end, is held pressed against a cam disk 38 of the machine shaft 2. When the rod 31 by the cam disk is pushed down its motion is transferred to the rod 30 by a spring 40. Said spring is enclosed in a sleeve 41 which is constricted at the top and which is mounted on the rod 31 by means of a 30 pin 42. Into the lower end of the sleeve 41 is screwed a sleeve 43 which is adapted to slide on the rod 30. The spring 40 rests with one end against the top of the sleeve 41 and with the other end against a ring 44 which is mounted on the rod 30. When the rod 31 is raised by the 35 spring 36 it, in its turn, raises the rod 30 by means of the sleeves 41 and 43 and the ring 44. By means of the screw sleeve 43 the spring 40 is more or less compressed in order to regulate the pressure of the insertion member 21 against the 40 cork disk. The tension of the spring is adjusted so that if the part 21 meets a greater resistance than is normally necessary for the insertion of the cork disk into the cap the spring is compressed whereby the sleeve 43 slides on the rod 31. 45 This motion of the two sleeves 41 and 43 relative to the rod 31 is utilized to declutch the drive device of the machine.

50 For this purpose the sleeve 41 is provided with a small arm 46 adapted to be swung on a pivot 47 in the upper end of the sleeve. The lower end of this arm has a cam face 48 which at the downward motion of the sleeve 41 when the rod 30 stands still meets a corresponding cam surface of a ring 49 secured to the rod 30 which results in 55 that the arm 46 is turned to the left in the drawings (Figure 2) and pushes against a push member 50 mounted in a guide 51 of the slide 7. The push member 50 engages and moves an upright rod 53 the upper portion of which is pivoted as indicated at 53^a to accommodate this movement. The rod 53 is mounted to slide vertically and is guided partly by means of the table 22 through which it passes and partly by a guide member 54^a fixed on the frame 1. When the rod 53 is displaced by the movement of the push member 50 the upper extremity thereof is moved in the path of a shoulder 54 carried by the slide 5. 60 The slide 5 in Fig. 1 is shown in its uppermost 65 position and during the downward movement 70

75—86 thereof, if the rod 53 is disposed in the path of the shoulder 54, said rod 53 is moved downwardly. 5

80 The displacement of the rod 53 is utilized to automatically interrupt the operation of the machine and with this object in view the rod 53 is extended downwardly toward the lower part of the machine as illustrated in Figs. 7 and 8 and operates a friction coupling. The friction coupling is illustrated at 75—76 and may be of a conventional type adapted to transmit motion 10 from a driving belt pulley 77 to the shaft 78 from which latter motion is transmitted to the different parts of the machine by well known power transmitting devices such as gear wheels 78^a. The coupling element 75 is movable longitudinally on the shaft as usual by means of a collar 79^a, the collar being connected with rods 80 which latter in turn are connected with short upright arms 81 on the shaft 81^a pivotally mounted on the base of the machine. The shaft 81^a 20 is provided with another arm 82 disposed in a substantial horizontal position and connected through a rod and lever 83—84 with the lower extremity of the rod 53. Thus when the rod 53 is depressed by the shoulder 54 an upward movement is imparted to the arm 82 through the lever 84 and rod 83 and by means of the arms 81 and rods 80 the coupling element 75 is displaced so as to disengage the companion coupling element 76 against the tension of the spring 85 and in 30 this manner the operation of the machine is interrupted.

35 The machine operates in the following manner. Normally the two rods 30, 31 move as a single rod. Should there arise any perturbation 40 when laying in the cork the part 21 will immediately meet a greater resistance than the usual and normal one. Consequently, movement of the part 21 is arrested but movement of the members 33, 31 and 41 continues. As the rod 30 is 45 directly coupled with the member 21 through the lever 26, its motion is also arrested, and during the descending movement of the sleeve 41 and arm 46, the extremity of the latter engages and is swung outwardly by the cam ring 49 resulting in actuation of the push member 50 and the actuation of the control device connected therewith.

50 The same will be the case, as already mentioned, even if there is no cork disk or if the 55 disk is broken. There is namely a stopping member 64 in the machine table 1 which member is movable towards and away from the insertion member 21. If there is no cork disk or if the bore for the member 21 is not entirely filled (viewed in the cross direction) by a cork disk inserted into the same the stopping member, by the action of a spring 65, engages a recess 67 of the part 21 and prevents it from moving upward (see Figure 3). As is clear from Figure 1, the 60 spring 65 is located between a shoulder 68 of the part 64 and a sleeve 69 which is screwed into the hole for the stopping member in question. When, on the other hand, a whole cork disk is fed to the insertion position it carries away the stopping member so that the part 21 may be pushed upward. Also this device operates quite automatically, as will be easily seen.

65 Cork particles which may lie on the member 21 are pushed down by the cork disks into a 70 waste chute 72 which in the drawings is shown disposed in the member 21, but which may also be disposed laterally thereof. As to the members 46, 50 and 53 they may be substituted for by for 75 instance the device shown in Figure 4. Instead of 75

the swingable arm 46, the sleeve 41 is provided with a stationary arm 57 having a push tap 58. This co-operates on one hand with the ring 49, on the other hand with an angle-lever 59, which 5 is connected to the rod 53. By this arrangement the machine may be declutched without the co-operation of the slide 5.

It need hardly be pointed out that the described device also is applicable to other disk 10 packings than to those of cork, and also in other machinal combinations.

Having now described my invention, what I claim as new and desire to secure by Letters Patent is:

15 1. In a machine of the character described, a device for introducing cork and like inserts into bottle caps, said device including two movable members, one of said members being adapted to seize the cap and the other member being movable 20 to effect insertion of the cork insert in the cap, a drive member, a driving connection between the drive member and the movable inserting member, said driving connection including a yieldable member permitting movement of the 25 drive member relative to the inserting member, and a control member operated in response to actuation of said yieldable member.

2. In a machine of the character described, a device for introducing cork and like inserts into 30 bottle caps, said device including two relatively movable members, one of said members being adapted to hold the cap and the other member being movable to effect insertion of the cork insert in the cap, a drive member, a driving connection 35 between the drive member and the movable inserting member, said driving connection including relatively movable rods and a spring interposed between said rods, a member movably carried by one of said rods and a cam device 40 carried by the other rod engaging and operating said movable member upon relative movement of said rods, and a control member operated by said movable member.

3. A machine as claimed in claim 2, characterized in that the movable member carried by the

first mentioned rod is connected with a sleeve attached to said rod, said sleeve receiving said spring, and a threaded member fitted in said sleeve and slidably receiving the second mentioned rod, the tension of said spring being regulated by adjustment of the threaded member.

4. A machine as claimed in claim 1, characterized by the provision of means for feeding cork and like inserts into position with respect to the cork inserting member, a locking member normally disposed in the path of and obstructing movement of the inserting member and engaged and moved to inoperative position by perfect and accurately positioned cork inserts advanced by 10 said feed means.

5. A machine as claimed in claim 1, characterized by the provision of means for feeding cork and like inserts into position with respect to the cork inserting member, a locking member normally disposed in the path of and obstructing 15 movement of the inserting member and engaged and moved to inoperative position by perfect and accurately positioned cork inserts advanced by 20 said feed means, said locking member being mounted for reciprocating movement and said inserting member having a passage extending therethrough terminating adjacent the locking member for permitting the discharge of particles 25 of cork broken or detached during operation of the machine.

6. In a machine of the character described, a device for introducing cork or the like inserts into bottle caps, said device including two movable members, one of said members being adapted to seize the cap and the other member constituting a 30 plunger to effect insertion of the cork insert in the cap held by the first mentioned member, a drive member, a driving connection between the drive member and the plunger, said driving connection including a yieldable member permitting 35 movement of the drive member relative to the plunger, and a control member operated in response to actuation of said yieldable member.

ANDERS JOSEF JONSSON.
